UNITED STATES PATENT OFFICE.

LUTHER G. McALISTER, OF TULSA, OKLAHOMA.

RAIL JOINT.

Application filed March 21, 1922. Serial No. 545,451.

To all whom it may concern:

Be it known that I, LUTHER G. McALISTER, a citizen of the United States, residing at Tulsa, in the county of Tulsa and State of Oklahoma, have invented new and useful Improvements in Rail Joints, of which the following is a specification.

My present invention has reference to railway construction.

10 In carrying out my invention it is my purpose to produce railway rails of a construction whereby the same will so interengage at the meeting ends thereof as to hold all of the rails in positive alignment and 15 prevent the vertical or lateral movement of the rails at the joints thereof.

It is also my purpose to produce in a railway construction, rails which have their webs offset adjacent to the ends of their base 20 portions and their webs extending beyond their base portions, the heads of the rails beyond the offset portions of the webs and on the extension of the webs being cut away at angles to their juncture with their 25 webs to provide pockets for the head sections on the coacting rail, the projecting web of each of the rails resting on the base of the coacting rail, the ends of the webs contacting with the shoulders provided by 30 the offset portions on the webs of the coacting rails, and the base of each of the rails meeting, while means is passed transversely through the lapping webs of the rails adjacent to the ends thereof for connecting the 35 rails.

A further object is to produce in a railway construction, rails having interengaging means for associating the same to hold the heads thereof in alignment and to prevent 40 lateral or sinking motion, but which will permit of the necessary longitudinal movement incident to expansion and contraction.

The drawings which accompany and form part of this specification, illustrate a satisfactory embodiment of the improvement reduced to practice, and wherein:

Figure 1 is a top plan view of rails constructed and connected in accordance with this invention.

50 Figure 2 is a side elevation.

Figure 3 is a sectional view on the line 3-3 of Figure 2.

Figure 4 is a sectional view on the line 4-4 of Figure 2.

55 Figure 5 is a perspective view of one of the rail ends.

Figure 6 is a plan view of the rails separated.

Ends of the rails constructed in accordance with this invention are substantially 60 similar, except that it may be found desirable that the projecting webs of the rails be offset to the opposite sides of the web proper at the opposed ends of the rails, and also that the head at the ends of the rails be cut 65 away at different angles.

Referring now to the drawings in detail, the numerals 1 and 2 designate contiguous rails and 3 the ties on which the rails rest and to which the rails are spiked.

The rails 1 and 2 have their body portions constructed in the usual manner to include a base 4, a web 5, and a head 6. In the present instance the ends of the base flanges 4 of both of the rails 1 and 2 are cut angularly, 75 the said angle ends being indicated by the numerals 7 and 8 respectively. The webs 5 of the rails, inward of the ends 7 and 8 of the base portions thereof are, for a suitable distance, offset from the webs proper, thus 80 providing shoulders 9 and 10 between the webs 5 and the web extensions 11 and 12 respectively. The extensions 11 and 12 of the respective rails are parallel with the webs 5 thereof, and project a suitable distance beyond the ends 7 and 8 of the said rails. The projecting portions or extensions of the webs have both their upper and lower faces flat, and the base flanges 4 of the rails, 85 in a line with the inner faces of the web extensions 11 and 12 for a width equalling the thickness of the shoulders 9 and 10 are likewise flat, and these flat portions are, for distinction, indicated by the numeral 13 respectively. Also the web extensions 11 and 12 90 gradually increase in thickness from their upper to their lower flat edges so that the widened lower portions will have an effective bearing on the surfaces 13.

Outward of the shoulders 9 and 10, and 100 both inwardly and outwardly with respect to the ends 7 and 8 of the base flanges of the rails, the extensions 11 and 12 thereof have their head portions cut away at determined intervals, providing spaced head blocks 14 105 respectively. The ends of the head blocks are cut at the same angle as indicated by the numeral 15 respectively, and the spaces 16 between the head blocks on one of the web extensions provide pockets for the head 110 blocks on the coacting rail extension. It will thus be apparent that the rails must be

moved angularly in associating the same, and when associated, the ends of the web extensions 11 and 12 will contact with the shoulders 9 and 10 respectively, and the 5 angle ends 7 and 8 of the rails will abut. There is, however, sufficient space between the head blocks 14 and the walls of the pockets in which they are received to permit of the necessary longitudinal movement of the 10 rails incident to expansion and contraction.

Each web extension, 11 and 12, adjacent to its ends is provided with bolt openings 17 respectively, and when the web extensions have their confronting faces in contacting 15 engagement, these openings align, and there are passed therethrough bolts 18 which are engaged by nuts 19. This connecting means positively holds the rails against lateral movement, while the lower portions of the 20 head blocks which project laterally from the web extension on which they are formed have their under faces flat and find a firm bearing on the upper flat edge of the base extension on which they rest, so that downward 25 movement of the rails at the ends thereof cannot occur. In addition to this, the flat under faces of the web extensions resting on the surfaces 13 more effectively hold the rails against any tendency for 30 downward movement, and in addition to this, the contacting engagement between the upper and lower edges of the rails with the under faces of the head blocks and with the 35 said surface 13 prevent an upward movement of the rails.

The inner lower corners of the heads of the rails are slightly beveled, as disclosed by the drawings to permit of the ready insertion in the fishing space therebetween of 40 the cooperating rail sections.

Having described the invention, I claim:—

1. The contiguous ends of railway rails, each having its web offset adjacent to the 45 end and said web extending beyond its base, and its said web extension having the head

portion of the rail cut away at intervals to provide head blocks, and wherein the spaces between the head blocks on one of the rails form pockets for the reception of the head 50 blocks on the other rail.

2. The abutting ends of railway rails, each rail having its web offset adjacent to the end and the said offset portion of the web extending beyond the end of the base, the 55 head of the rail on the said web extensions being cut away at spaced intervals to provide head blocks, the end walls of the head blocks being cut at the same angle and the spaces therebetween providing pockets for 60 the head blocks of the coacting rail, the end of the web extensions of each rail designed to contact with the shoulder at the offset portion of the web of the coacting rail when the rail ends are associated, and means 65 passing transversely through the web extensions for connecting the same.

3. Contiguous rails, each having its base flange terminating in an angle end, its web offset inwardly of the end and extending 70 beyond the end of the base flange, said base flange in a line with the shoulder provided by the offset being flat, and the upper and lower edges of the web extensions being likewise flat, said web extensions gradually increasing in thickness from their upper to 75 their lower edges and being provided adjacent to their ends with openings, each of said web extensions having its head cut away at equi-distantly spaced determined intervals to provide head blocks, and the opposed walls of the head blocks being cut at the same angle and the spaces therebetween forming pockets for the reception of the head blocks of the coacting rail, the openings in the web extensions aligning when the head blocks are received in the pockets, and means 80 passing transversely through said openings for connecting the web extensions.

In testimony whereof I affix my signature. 90

LUTHER G. McALISTER.
